ABSTRACT

A bale of bags is provided which is strapped about the thickest areas of the bag bottoms. A sleeve of paper is wrapped about the bale at right angles to the direction of the straps.

FIG. 3

1
BAG BALE

This is a continuation in part application of an application for Bag Bale Ser. No. 120,543 filed Mar. 3, 1971 entitled "Bag Bale", now abandoned.

This invention relates to an improvement in Bag Bale and deals particularly with a package of bags which are normally of the grocery bag type.

BACKGROUND OF THE INVENTION

In our previous application above referred to, a series of hands of bags, usually 25 bags to each hand, are stacked with the thicker ends of the bags in opposed relation. Alternate hands of bags are reversed relatively to the others so that the resulting stack is of substantially equal thickness at each end. The bags are compressed together under high pressure, and straps are applied about the stacks to form a bale. The straps are positioned so as to encircle the thickest portions of the bag body.

While such bales have been successfully used, one difficulty has been experienced. In order to effectively strap the bales, the straps must be spaced several inches from the ends of the bale, as this is the area of the bag which is thickest. As a result, there has been a tendency for the ends of the bags, outwardly of the straps, to fan out after baling so that the ends of the bale are somewhat thicker than the center portions thereof. As a result, when the bags are palletized with alternate rows of bales extending crossways of the bags of the lower layer in order to provide stability to the pallet, a slight instability is produced by the outwardly fanned bag ends. Furthermore, while the pallets of bags are normally protected by an outer wrapping of plastic or paper, once the pallet is opened and the enclosing wrapper is removed, the remaining bales on the pallets are open to contamination in a warehouse or the like. It is an object of the present invention to avoid these previous difficulties.

SUMMARY OF THE INVENTION

An object of the present invention resides in the provision of a sleeve extending about the bale designed to overlie the upper bag of the bale and to underlie the lower bag thereof. The wrapper extends about the bale in a direction at right angles to the straps holding the bale together. The paper sleeve is secured in tubular form while the bags are under compression. As a result, the sleeve holds the bag ends from fanning out and also acts as a protection for the bag surfaces. Any tendency for the straps to stretch is reduced by the presence of the encircling sleeve. The baling straps hold the bale from expansion while the encircling sleeve holds the bag ends from fanning out. As a result the rectangular form of the bag is maintained and the resulting bales will stack more evenly upon a supporting pallet and the bales are held in generally rectangular form.

A further feature of the present invention resides in the provision of a bale having baling straps extending about the bags in a direction transversely of their length and in providing a sleeve encircling the bale and extending longitudinally of the length of the bags. This sleeve not only holds the bale of bags in substantially rectangular relation, but also prevents any tendency for the bags to slide longitudinally.

2

These and other objects and novel features of the present invention will be more clearly and fully set forth in the following specification and claims.

BRIEF DESCRIPTION OF THE DRAWINGS

FIG. 1 is a perspective view of a bale of bags, showing the general arrangement thereof.

FIG. 2 is a perspective view of the bale before the ends of the encircling sleeve are attached together.

FIG. 3 is a side elevational view of the bale.

DESCRIPTION OF THE PREFERRED EMBODIMENT OF THE INVENTION

As was described in the previous application above referred to, the bags A are stacked to form hands of bags arranged with the bottom ends of the bags in superimposed relation. While the open ends of the bags are of a thickness of four plies of paper, the bottom ends of the bags are of a thickness which is usually 8 or 10 plies. Usually the bags are of 8 ply thickness at their extremity when flat while an area of the bottom which is spaced usually several inches from the bottom extremity of the folded bags is of 10 ply thickness.

The hands of bags 10 are stacked with the bottom ends of the bags of one hand overlying the top ends of the bag of the next adjacent hands. By providing an even number of hands in the bale, the ends of the stack are of substantially equal thickness. The stack of bag hands are placed under high compression by suitable means such as a hydraulically operated platen press, and straps or bands 11 are secured about the stack to hold them in compressed form. The resultant bag of bale requires substantially 30% less space than a stack of bags which are not compressed in the same manner.

To complete the bale, an elongated strip of paperboard 12 is wrapped about the bale in a direction at right angles to the straps 11. The strip of paper 12 is of a width substantially equal to the width of the bags, or may be of greater width if it is desired to also enclose the side edges of the bag. As indicated in the drawings the sheet of paperboard 12 includes a panel portion 13 designed to extend over an end of the series of bags, and top and bottom panels 14 and 14' designed to extend over and under the bale. An end flap 15 is folded upwardly to enclose to opposite ends of the bale, and adhesive 16 is applied to the inner surface of a top flap 17, and this flap is folded to overlie the flap 15 and is secured thereto. The sheet 12 is applied while the bale is under compression so that when the bale is released from compression, the bags are held from fanning outwardly of the straps 11 the sheet 12 also preventing the hands of bags from shifting longitudinally during shipment or handling.

The sheet 12 serves as a cover for the bale after the pallet has been opened and prevents contamination of the outer bags of the bale. Furthermore the sheet 12 extends in a direction at right angles to the straps 11 so as to form solid blocks of material which are virtually rectangular in form and may be readily palletized in stable loads. As a matter of fact, the pallets may be stacked one above the other to the height of several pallets without danger of tipping over.

In accordance with the Patent Statutes, I have described the principles of construction and operation of my improvement in Bag Bale; while I have endeavored to set forth the best embodiment thereof, I desire to

have it understood that obvious changes may be made within the scope of the following claims without departing from the spirit of my invention.

We claim:

1. A bale including:
 a plurality of bags in a flat form,
 a transverse area near one end of each bag being of
 substantially greater thickness than the other end
 thereof said area of greater thickness being on one
 side of the center of the length of the bags,
 said bags being stacked with said one end, of substan-
 tially one half of the bags overlying the other end
 of the remaining bags,
 said bags being held in compressed state by a pair of
 straps extending transversely about the stack, said
 straps being located about the areas of substantially

greater thickness, and
 a wrapper encircling the bags and extending in a di-
 rection at right angles to said straps.

2. The bale of FIG. 1 and in which the ends of the
 5 wrapper are secured together.

3. The structure of claim 1 and in which the wrapper
 is formed of paper.

4. The structure of claim 1 and in which the wrapper
 10 includes an end portion extending along one end of the
 bale, upper and lower portions extending over and
 under the bale, and end portions in overlapping rela-
 tion.

5. The structure of claim 3 and in which the end por-
 15 tions of the wrapper are secured together by adhesive.
